DESIGN FOR A TOY WHEELBARROW

Arthur L. Chetlain, Seattle, Wash.

Application August 22, 1936, Serial No. 64,533

Term of patent 3½ years

To all whom it may concern:

Be it known that I, Arthur L. Chetlain, a citizen of the United States, residing at Seattle, King county, Washington, have invented a new, original, and ornamental Design for Toy Wheelbarrows, of which the following is a specification, reference being had to the accompanying drawing, forming part thereof, wherein—

Fig. 1 is a side elevation of a toy wheelbarrow embodying the present design.

Fig. 2 is a perspective view of the same.

Fig. 3 is a plan view.

I claim:

The ornamental design for a toy wheelbarrow, as shown.

ARTHUR L. CHETLAIN.
